Des. 210,714
Patented Apr. 9, 1968

210,714 •

SHOE SOLE OR SIMILAR ARTICLE

Jean Pradet, Saint Jean-de-la-Ruelle, France
(18 Rue de la République, 45 Orleans, France)

Filed Dec. 28, 1966, Ser. No. 5,201

Claims priority, application France June 28, 1966

Term of patent 14 years

(Cl. D2—320)

FIG. 1 is a side elevational view of a shoe sole showing my new design;

FIG. 2 is a bottom plan view thereof;

FIG. 3 is a cross-sectional view along the line III—III of FIG. 2; and

FIG. 4 is a partial cross-sectional view along line IV—IV of FIG. 2.

I claim:

The ornamental design for a shoe sole or similar article, substantially as shown.
